US00D625327S

(12) **United States Design Patent**
Fitzmaurice et al.

(10) **Patent No.:** **US D625,327 S**
(45) **Date of Patent:** ** *Oct. 12, 2010

(54) **ICON FOR A PORTION OF A DISPLAY SCREEN**

(75) Inventors: **George Fitzmaurice**, Ontario (CA); **Gord Kurtenbach**, Ontario (CA); **Justin Matejka**, Ontario (CA); **Marsha Leverock**, Ontario (CA); **Paul D. Vaters**, Ontario (CA)

(73) Assignee: **Autodesk, Inc.**, San Rafael, CA (US)

(*) Notice: This patent is subject to a terminal disclaimer.

(**) Term: **14 Years**

(21) Appl. No.: **29/309,691**

(22) Filed: **Sep. 26, 2008**

Related U.S. Application Data

(63) Continuation-in-part of application No. 12/200,373, filed on Aug. 28, 2008.

(51) **LOC (9) Cl.** **14-04**

(52) **U.S. Cl.** **D14/489**

(58) **Field of Classification Search** D14/485-95; D18/24-33; D19/6, 52, 9, 10; D20/11; D21/324-33; 715/700-867, 973-77
